UNITED STATES PATENT OFFICE.

ISAAC Q. GURNEE, OF BUTLER, NEW JERSEY, ASSIGNOR TO THE BUTLER HARD RUBBER COMPANY, OF NEW YORK, N. Y.

ATOMIZER.

SPECIFICATION forming part of Letters Patent No. 601,616, dated March 29, 1898.

Application filed October 26, 1897. Serial No. 656,454. (No model.)

To all whom it may concern:

Be it known that I, ISAAC Q. GURNEE, of Butler, county of Morris, and State of New Jersey, have invented a new and useful Improvement in Pocket-Atomizers; and I do declare the following to be a full, clear, and exact description of the invention, such as will enable others skilled in the art to which it appertains to make and use the same, reference being had to the figures marked on the accompanying drawings, which form a part of this specification.

Figure 1 represents a perspective view of an atomizer to which my invention has been applied, showing the cap-piece detached. Fig. 2 is a central vertical section of the atomizer. Fig. 3 is a similar section of a modified form of atomizer. Fig. 4 is a detailed perspective view of the piston-chamber and the piston-rod and handle. Fig. 5 is a perspective view of the screw-cap of the vial or reservoir.

My invention consists of the following construction and combination of parts, the details of which will first be set forth and described and the patentable features of which then pointed out and claimed.

In the drawings, Figs. 1 and 2 represent a pressure form of atomizer, while Fig. 3 represents a suction form of the same. The details in Figs. 4 and 5 are applicable to either form.

My invention relates to atomizers, and more particularly to pocket-atomizers, in which the vial and air-forcing means are associated in a compact shape.

1 is the liquid-holding vial. 2 is the plunger-chamber. These are preferably formed or molded in one piece, as shown. I have found that hard rubber is an excellent material for use in making my invention, although any suitable material may be employed. A third or auxiliary chamber 3 is formed in the upper end of the atomizer 45 and is separated from chamber 2 by a diaphragm 4.

In the pressure form of atomizer a screw-cap 5 covers the end of the auxiliary chamber 3 and carries the atomizer tip and nozzle 6, which may be of any of the usual constructions. The liquid-tube 7 of the atomizer pro-

jects inwardly beyond the air-tube 8 and passes through an opening 9 between the chamber 3 and the vial 1 down into the bottom of the latter. The liquid-tube 7 fits loosely in the opening 9, so there is an air communication between chambers 3 and 1. 10 is an air port or opening through the diaphragm 4 between chambers 2 and 3.

In the operation of the pressure form of atomizers the liquid to be atomized is introduced into the vial 1 through the screw-cap 11. Upon operating the piston 12 by the handle 13 and plunger-rod 14 air is forced through the opening 10 into the auxiliary chamber 3 under pressure, a portion of which pressure enters the vial 1 through the opening 9, thereby forcing the liquid therein out through the liquid-tube 7 into the atomizer-tip 6, while a portion enters the air-tube 8 and is conveyed to the tip. An atomizing action then takes place in a manner well understood and not necessary to be here described.

In the operation of the suction form of atomizer shown in Fig. 3 the opening 4 is continued by means of a tube 15 directly to the atomizer-tip 16, the air issuing from the tip inducing a suction action through the liquid-tube 7, causing the liquid to be drawn out of the vial 1 and atomized in the usual way. In this construction the tube 7 may fit tightly at the point where it passes from the chamber 3 into the chamber 1.

The cap 17 is adapted to fit over the atomizer shown in either Figs. 1 and 2 or that form shown in Fig. 3, so as to protect the parts when carried in the pocket.

In the suction form a spray nasal nozzle 18 is employed, which screws into the open end of the auxiliary chamber 3. When the atomizer is not in use, it is closed by a screw-cap 19, (shown in dotted lines in Fig. 1 and in full lines,) secured to the end of the plunger-handle 13 when the atomizer is being used, the nozzle 18 being suitably threaded for this purpose.

The handle 13 when the atomizer is not in use is intended to be unscrewed from the plunger-rod and reversed and its opposite end screwed upon the threaded boss 20 upon the plunger-cap 21, it being provided with suitable threads 22 for that purpose. To secure

this result, the outer end of the plunger-rod 14 is provided with pins or projections 23, which take into corresponding slots 24 in the boss or collar 20 and prevent the plunger-rod from rotating when the handle 13 is unscrewed for the purpose of removing it and reversing it, so that the thread 22 fits upon the threaded boss 20, as shown in Fig. 1. This serves to make a compact device for pocket use when the atomizer is not in action.

The vial screw-cap 11 is provided with one or more slots 25 parallel with the axis of the cap and extending along the periphery of the threads. By this means the liquid in the vial 15 and that retained by the screw-threads is forced out into these vertical passages 25 and drained back into the vial, and the tendency of the liquid to ride up the screw-threads when the cap is being screwed down is prevented. The accumulation of liquid on the outside of the screw-cap is thereby obviated.

My atomizer is a compact serviceable pocket device which is the result of the association and arrangement of the operative devices in 25 the manner shown and described.

In order to produce a compact atomizer adapted for pocket use, (preferably the vest-pocket,) it is highly desirable that the plunger-chamber and the vial be substantially the 30 same length and be formed alongside each other, with a side wall or partition common to both, that the atomizer-tip and the mouth of the vial be at one or the upper end to prevent any leakage, and the handle of the plunger-rod at the other or lower end. This is the 35 first compact vest-pocket atomizer that I am aware of having been produced. Both the atomizer-tip and the vial-mouth are protected by a single cap-piece. Any leakage from a 40 pocket-atomizer is a vital defect where fluids are used which will soil the apparel in which the atomizer is carried.

Having described my invention, what I claim, and desire to secure by Letters Patent, 45 is—

1. An atomizer comprising a plunger-chamber and a vial located side by side having a side wall common to both, an atomizer-tip and a cap for the vial at the top and a plunger-

rod and a cap at the bottom of the atomizer, 50 and a liquid-tube leading from the atomizer-tip through the common side wall to the bottom of the vial.

2. An atomizer comprising a plunger-chamber and a vial located side by side having a side wall common to both, an atomizer-tip and a cap for the vial at the top and a plunger-rod and a cap at the bottom of the atomizer, 55 an auxiliary chamber interposed between the atomizer-tip and plunger-chamber, and a liquid-tube leading through the auxiliary chamber and common side wall to the bottom of the vial.

3. An atomizer comprising a plunger-chamber, a plunger-rod, a detachable handle for 60 said rod, means for securing the handle to the rod, and means for detaching the handle and securing it to the plunger-chamber over the rod.

4. An atomizer comprising a plunger-chamber, a plunger-rod, means for locking the rod against rotation, a detachable handle for the rod, and means for securing the handle to the plunger-chamber over the rod.

5. The combination of a plunger-rod, a plunger-chamber, means for positively locking the rod against rotation and a threaded handle upon the plunger-rod.

6. An atomizer comprising a plunger-chamber, a plunger-rod, a movable handle upon 80 the rod, interlocking means upon the chamber and the outer end of the rod for holding the rod against rotation while the handle is being removed or replaced.

7. An atomizer comprising a vial and a plunger-chamber located side by side having a side wall common to both, a plunger having its handle extending out through the bottom of the plunger-chamber, an atomizer-tip formed above the upper end of the plunger-chamber, 85 and the vial-mouth formed at the upper end of the atomizer at one side of the atomizer-tip.

In testimony whereof I affix my signature in the presence of two witnesses.

ISAAC Q. GURNEE.
